UNITED STATES PATENT OFFICE.

AUGUST KORTENBACH AND KARL WORRING, OF WEYER, GERMANY.

UMBRELLA.

SPECIFICATION forming part of Letters Patent No. 781,433, dated January 31, 1905.

Application filed October 26, 1904. Serial No. 230,090.

To all whom it may concern:

Be it known that we, AUGUST KORTENBACH and KARL WORRING, citizens of the Empire of Germany, residing at Weyer, in Rhineland, in the Empire of Germany, have invented a new and useful Umbrella, of which the following is a specification.

Our invention relates to improvements in umbrellas and parasols with tubular metal sticks, whereby the umbrellas and parasols are rendered slender and light, as is required by the leading fashion.

The objects of our improvement are, first, to so reduce the upper part of the tubular metal stick in diameter in several steps that it tapers to the end; second, to apply the umbrella-notch to one of the steps of the tubular metal stick; third, to provide the thin end of the tubular metal stick with a female screw-thread; fourth, to provide a screw-threaded top piece which engages in the female screw-thread of the tubular metal stick; fifth, to provide a conical metal tube secured on the top piece and inclosing the reduced part of the tubular metal stick down to a point near the notch, and, sixth, to provide a conical cap for securing the wide end of the conical metal tube on the tubular metal stick and leading up to the flanges of the notch. We attain these objects by the umbrella or parasol illustrated in the accompanying drawings, in which—

Figure 1 is an elevation of a top piece, a conical metal tube, and a conical cap put together. Fig. 2 is an elevation of the upper reduced part of a tubular metal stick. Fig. 3 is an elevation of the top piece alone. Fig. 4 is a vertical longitudinal section through the conical metal tube alone. Fig. 5 is a vertical longitudinal section through the conical cap alone. Fig. 6 is an elevation of an umbrella-notch. Fig. 7 is a plan of the same; and Fig. 8 is an elevation of the upper part of the umbrella or parasol, the upper end of the tubular metal stick, the conical metal tube, and the conical cap being shown in section, the left and the right ribs being alone shown and the canopy or cover being omitted.

Similar characters of reference refer to similar parts throughout the several views.

According to our invention the upper part

of the tubular metal stick 1 is reduced in diameter in several (here three) steps 2, 3, and 4, so that the stick 1 tapers toward the upper end. Otherwise the stick 1, which is circular 55 in cross-section, may be made or shaped as usual.

6 denotes the ordinary stop for limiting the stroke of the runner. (Not shown.)

The umbrella-notch 7 (see Figs. 6 and 7) is applied to one (here the second) step 3 of the stick 1 intermediate the two ends of this step, as shown in Fig. 8. The notch 7 may be secured on the stick 1 by means of a pin 9, as usual. The notch 7 is in a known manner 65 pivotally connected with the several ribs 10 10, a wire being passed through the top eyes of the ribs 10 10 between the two flanges of the notch 7 and closed. The ribs 10 10 are shown as made of U-shaped steel bar; but they 70 may also be of any other known construction.

The upper end of the tubular metal stick 1 is in any known manner provided with a female screw-thread 5, in which the screw-threaded part 11 of a top piece 12 (shown at 75 Fig. 3) can engage. The intermediate part 13 of this top piece 12 may be cylindrical or slightly conical, it tapering in this case upward. Preferably this intermediate part 13 is made rough in some manner—for instance, 80 it may be provided with several longitudinal grooves 14, as shown.

From an inspection of Figs. 2 and 8 it will be evident that the reduced part of the tubular metal stick 1 above the notch 7 does not 85 look nice or strong. For this reason a conical metal tube 15 (see Fig. 4) is employed, which is to inclose the reduced part of the stick 1 between the top piece 12 and the notch 7. The narrow end of this tube 15 is 90 made slightly larger in its internal diameter than the intermediate part 13 of the top piece 12, so that this part 13 can be introduced into the tube. Afterward the tube 15 is pressed on the intermediate part 13 by means of a 95 suitable machine-tool, whereby the tube 15 is rigidly connected with the top piece 12. The grooves 14 or other roughness of the intermediate part 13 prevent the two parts 15 and 12 from getting loose and shifting. The 100 screw-threaded part 11 of the top piece 12 can be introduced into the female thread 5 of

the stick and screwed home by turning the tube 15 with the hand until the end face of the stick 1 bears against the shoulder 16 of the top piece 12. The conical metal tube 15 is preferably made thin, so as to reduce as much as possible its weight. Then it would be liable to bending and becoming distorted during the screwing operation or the use, and thereby getting off the top piece 12. To prevent this, a conical cap 17, (see Figs. 1 and 5,) produced from sheet metal by drawing or otherwise, is employed, whose reduced part 18 can be fitted tightly into the wide end of the conical metal tube 15, so that the lower edge 15 of the latter bears against the shoulder 19 of the cap. At the upper edge the cap 17 is bent, whereby it and therewith also the tube 15 is stiffened. The bent edge of the cap has an internal diameter like that of the stick 1 above the notch 7. It will now be obvious that by the cap 17 resting on the stick 1, the tube 15 will be not only supported, but also centered. The cap 17 may be made a little more conical than the tube 15 and is made a little 25 larger in diameter at its lower edge than the flanges of the notch 7. Thus the conical tube 15 will render the upper part of the stick stronger in appearance, and by means of the cap 17 it will lead up from the top piece 12 to the canopy or cover on the ribs 10 10 in the folded state of the umbrella or parasol. Thereby the umbrella or parasol is made to look somewhat like a walking-stick.

It is obvious that the part of the tubular metal stick 1 requires to be cylindrical up to 35 the stop 6 for properly guiding the runner, and therefore it is the part above the stop 6 which according to our invention is reduced in diameter in several steps, and thereby made to taper upward to the upper end.

The umbrella or parasol described so far may be varied without deviating from the spirit of our invention.

What we claim as our invention, and desire to secure by Letters Patent, is—

1. An umbrella-stick, a notch thereon, a top piece detachably connected to the stick and having a grooved exterior surface, a tube secured to said grooved surface and a cap having a portion for engaging in said tube 50 and a portion for engaging over the notch.

2. A tubular umbrella-stick, a notch thereon, a top piece having screw-thread engagement with the stick, a tube attached to the top piece, and a cap having a reduced portion for engaging in said tube, and flared portion for engaging over the notch.

In testimony whereof we have signed our names to this specification in the presence of two subscribing witnesses.

AUGUST KORTENBACH.
KARL WORRING.
